UNITED STATES PATENT OFFICE.

ELLIOTT S. NORTON AND CHARLES J. BERNDT, OF CHICAGO, ILLINOIS, ASSIGNEES TO
ACMIE STEEL GOODS COMPANY, OF CHICAGO, ILLINOIS, A CORPORATION OF ILLINOIS.

MACHINE FOR FORMING CORRUGATED METAL FASTENERS.

1,070,282.

Specification of Letters Patent.

Patented Aug. 12, 1913.

Application filed March 19, 1912. Serial No. 684,898.

To all whom it may concern:

Be it known that we, ELLIOTT S. NORTON and CHARLES J. BERNDT, citizens of the United States, residing at Chicago, in the county of Cook and State of Illinois, have invented certain new and useful Improvements in Machines for Forming Corrugated Metal Fasteners, of which the following is a specification.

Such fasteners are commonly made by severing into suitable lengths a steel ribbon which has been previously corrugated and sharpened upon one edge. Our invention relates more particularly to a machine for corrugating and sharpening the edge of the steel ribbon. The article resulting from the machines and processes of manufacture heretofore adopted has been more or less defective in that, by reason of the operations by which it has been formed the entering knife edge of the fastener is not smooth and sharp, but on the contrary is irregular and turned or formed with a bur. Our invention is a machine capable of producing in great quantity a corrugated strip of metal from which the fasteners may be formed, the strip having a smooth continuous cutting edge without bur or other irregularity. In our improved machine the strip is neither ground nor pressed to secure the required sharpness of cutting edge as in the machines of the prior art, but the corners of the cutting edge are chamfered by planing or shaving knives past which the strip is drawn by means of crimping or corrugating rolls. In order to avoid any possible irregular, turned or wire edge, the material upon the sides of the cutting edge is removed by a series of cuts, the first of which forms the extreme edge or apex of the strip into a comparatively blunt angle, the second at a somewhat more acute angle to the plane of the strip, removes the material somewhat farther back from the extreme edge of the strip, and the third and last cut made at an angle yet more acute with reference to the plane of the strip carries the chamfering nearly to the plane of the strip, all of which will appear more fully from an inspection of the accompanying drawings especially when taken with the detailed description below. The corrugating rolls in our machine are made to serve the further purpose of fur-

nishing the draft for drawing the strip of metal past the planing knives.

In the accompanying drawings we have shown a preferred embodiment of our invention and have detailed the same in the following detailed specification. It will be understood, however, that the disclosure of the specific form is only for the purpose of exemplification and that our invention is not limited thereto but its scope is set forth in the following claims.

In the drawings Figure 1 is a plan view of the preferred form of our invention partly in section upon the line 1—1 of Fig. 2; Fig. 2 is a vertically longitudinal section upon the line 2—2 of Fig. 1; Fig. 3 is a plan view on an enlarged scale of the planing or shaving knives and their mountings; Figs. 4 and 5 are side elevations of the same viewed from opposite sides of the machine; Fig. 6 is a central vertical section upon the line 6—6 of Fig. 3; Figs. 7 and 8 are front and rear end views respectively of the same portion of the machine, and Fig. 9 a vertical cross-section thereof upon the line 9—9 of Fig. 3; Fig. 10 is a greatly enlarged cross-section of the edge portion of a strip as formed upon our machine; Fig. 11 is a fragmentary plan view of that portion of the machine in which the corrugating rolls are mounted; Fig. 12 is a vertical section of the same upon the line 12—12 of Fig. 11; Fig. 13 is an elevation partly broken away of the reduced entering end of a strip adapted to be operated upon by our machine, and Fig. 14 is a perspective view of a metallic fastener, such as is formed by sub-dividing the strips produced by our machine.

Upon a suitable bench or support A are bolted a knife support B and a roll housing C containing a pair of corrugating and draft rolls, the bite of which is in line with the axis of the chamfering or planing device. The latter consists of a stand 15 bolted to the bench at 16 and carrying at its upper end the strip guide and knife support 17. The body of the latter consists of a generally rectangular block having in the center of its upper face a kerf or deep channel 18 of a width to receive the strip from which the corrugated fasteners are to be formed and of a somewhat greater depth, the lower portion of the kerf or channel being enlarged

by a rectangular offset 19, as clearly shown in Figs. 7, 8 and 9. If desired for convenience of manufacture or other reason, the block 17 may be formed in a plurality of sections. The guide and knife support is secured to the stand by means of a plate 20 (see Figs. 6 and 9) which is screwed to the top of the standard 15 and also attached to the strip guide and knife support by the screws 21. (See Fig. 6).

In the enlarged lower portion 19 of the strip guiding channel is inserted a comparatively heavy backing bar 21' which supports the strip 22 when in the guide and is adjustable by means of the screws 23, 24 mounted in brackets 25—25 and operating against the projecting ends of the bar. By this construction the strip may be accurately adjusted to produce the desired depth of cut by the knives. Upon either side the strip guide and knife support is provided with a series of knife seats, three being shown upon each side, and each consists in a channel or recess against the bottom of which the knife blade is clamped, the plane of the bottom being inclined and intersecting the kerf or strip guiding channel near its upper edge, and the walls of the recess are so spaced from each other as to fit the width of the blade and prevent edgewise movement thereof. The knife seats are staggered, as shown more particularly in Fig. 3, and inclined to the plane of the strip guide or kerf at successively greater angles from the front to the rear of the machine, though if desired the members of each pair may be arranged at the same angle. The knives 26—26 of the first pair are held to their respective seats by perpendicular bolts 27—27 which extend through tapped holes in the supporting blocks 28—28, the latter being bolted at 29—29 to the combined strip guide and knife support, and also cut away or relieved at 28'—28' to permit the shavings or chips to escape and facilitate uninterrupted operation of the knife blades. The members 30—30, 31—31 of the second and third pairs of planing knives are held to their seats by backing blocks 32—32 bolted to the strip guide at 33—33 and provided with projections 34—34 which enter the knife seats and bear upon the knives, their under faces being preferably formed to lie parallel with the bottoms of the knife seats when the backing blocks are bolted in place. It will be apparent that a strip of metal drawn through the kerf or strip guide with its edge extending into or across the planes of the several pairs of knives is chamfered as shown in Fig. 10, the knives of the first pair forming the extreme bevels 35—35, those of the second pair the intermediate bevels 36—36, and those of the third pair the final bevels 37—37 in the order given. It is to be observed also that the knives are forwardly inclined so

that they have a tendency to force and hold the strip in firm contact with the backing bar.

Referring now more particularly to Figs. 1, 2, 11 and 12, illustrating the corrugating rolls, it will be seen that the housing C is bolted at 38 to the bench A, and formed with the horizontal cross members 39—40 in which the bearings of the corrugating rolls are mounted. For this purpose the cross pieces are slotted as at 41—42, the slots being rabbeted at 43—44, and receiving the rectangular bearing blocks 45—46 for the arbor 47 of a stationary roll, and the adjustable bearing blocks 48—49 for the arbor 80 of the adjustable corrugating roll, all the bearing blocks being provided with shoulders 50—51 which coact with the rabbets 43—44 in the slots to prevent endwise displacement of the rolls or bearing blocks. 85 Each of the corrugating rolls 52—53 is provided with suitable spacing collars 54—55—56 and 57 and with one of the collars 58 which is freely revoluble upon the arbor of the adjustable roll, the inner head 59 of a screw 60 extending through an upright of the housing at 61 engages, to adjust the bite or pass of the rolls. Upon its lower end, the arbor 47 of the stationary roll carries a bevel pinion 62 which meshes with a similar pinion 63 upon a stub shaft 64 which carries at its outer end a gear 65 meshing with a gear 66 upon the power shaft 67, a pulley 68 being mounted on the power shaft for driving the same from any suitable source of power. 90

In order to start the operation of the machine upon a strip of metal the latter is somewhat narrowed or cut away on its entering end as at D, Fig. 13 in order that it may be inserted by hand through the strip guide without interference by the knives and drawn into the bite of the corrugating rolls. When this has been done the rolls draw the strip through the machine and the knives operate upon it successively as heretofore explained. 105

The operation of our invention is such that at a single pass therethrough the strip is sharpened and corrugated and by reason of the angular arrangement of knives adopted, the somewhat rounded or bipped cutting edge is formed without producing any burs, turned edge or other deformation, nothing remaining to be done but to cut the strip into lengths. As shown in Fig. 14 the ultimate product is a short piece of corrugated sheet metal having a smoothly and continuously beveled cutting or entering edge E and a squared driving edge F. 115

We claim:

1. In a machine of the character described, a stationary knife, a strip guide having a channel adapted to support a flexible strip of metal in operative relation to the knife with the planes of the strip and knife 130

- respectively inclined with respect to each other and the knife also inclined with relation to the length of the strip, and means for drawing the strip past the edge of the 5 knife.
2. In a machine of the class described, a strip guide, a pair of knives the edges of which are oppositely inclined to the plane of the strip guide and also with relation to 10 the length of the strip, said knives arranged to engage the adjacent corners of a strip of metal in the strip guide, and means for drawing a flexible strip through the strip guide.
- 15 3. In a machine of the class described, a strip guide, a plurality of pairs of knives arranged along the strip guide with their cutting edges at successively diminishing angles to the plane of the guide, and means for 20 drawing a strip with relation to the knives.
4. In a machine of the class described, a strip guide, knives arranged on opposite sides of the strip guide with their cutting edges in inclined position with respect to 25 the plane of the strip guide to chamfer the corners of a metal strip in the guide, and a pair of corrugating rolls adapted and arranged to draw a strip with relation to the knives.
- 30 5. In a machine of the class described, a strip guide having a channel for receiving a strip of metal to be chamfered, knives supported by and upon opposite inclined faces of the strip guide with their cutting edges 35 inclined to both the plane and length thereof, and means for drawing the strip through the guide.
6. In a machine of the class described, a strip guide having a strip receiving channel 40 and inclined seats formed on opposite sides of the strip channel, knives arranged in the seats with their edges inclined to the plane of said channel and in position to chamfer the edges of a strip in the guide, and means 45 for drawing a strip through the channel.
7. In a machine of the class described, a strip guide having a strip receiving channel, pairs of knife seats arranged along the strip guide, the seats of successive pairs being ar- 50 ranged at diminishing angles with relation to the plane of the strip channel, means for securing knives in the seats, and means for drawing a strip through the channel.
8. In a machine of the class described, a strip guide having a strip receiving channel 55 therein, an adjustable backing bar within the strip channel, knives arranged on opposite sides of the strip channel with their cutting edges inclined to the plane thereof for chamfering the upper edge of a strip in 60 said channel, and means for drawing a strip through said channel.
9. In a machine of the class described a strip guide having a narrow channel formed in a vertical plane, inclined knife blades ar- 65 ranged on opposite sides of the channel with their edges in position to chamfer a strip passing through the channel, the planes of the blades intersecting in the plane of the channel.
10. In a machine of the class described, a strip guide rectangular in cross section having a channel parallel to the sides thereof, knife seats formed in the guide the bottoms of which are in planes inclined to each other 70 and to the plane of the channel, knives in said seats, and means for securing said knives to the seats.
11. In a machine of the class described a strip guide rectangular in cross section hav- 80 ing a channel parallel to the sides thereof, knife seats formed in the guide the bottoms of which are in planes inclined to each other and to the plane of the channel, and intersecting substantially in the plane of the 85 channel, knives in the seats and means for securing the knives thereto.
12. In a machine of the class described a strip guide rectangular in cross section having a longitudinal strip channel parallel to 90 the sides thereof, knife seats formed in the guide the bottoms of which are in planes inclined to each other and to the plane of the channel, knives in the seats, and blocks se- 95 cured to the parallel sides of the guide hav- ing screws bearing upon and securing the knives on their seats.
13. In a machine of the class described a guide having a narrow channel extending longitudinally thereof, transversely extend- 100 ing, open ended, knife seats extending trans- versely of the guide and inclined to the plane of the channel thereof, and knives secured and longitudinally adjustable in said seats whereby the operative portion of the cutting 105 edges may be changed.
